UNITED STATES PATENT OFFICE.

GEORGE M. COKE, OF MILWAUKEE, WISCONSIN, ASSIGNOR TO THE FULLER-WARREN CO., OF MILWAUKEE, WISCONSIN, A CORPORATION OF WISCONSIN.

DESIGN FOR A GAS-RANGE.

40,701.

Specification for Design.

Patented May 17, 1910.

Application filed March 23, 1910. Serial No. 551,218. Term of patent 7 years.

To all whom it may concern:

Be it known that I, GEORGE M. COKE, a citizen of the United States, residing at Milwaukee, in the county of Milwaukee and State of Wisconsin, have invented a new, original, and ornamental Design for Gas-Ranges, of which the following is a specification, reference being had to the accompanying drawing, forming part thereof.

The figure is a perspective view of a gas range, showing my new design.

I claim:

The ornamental design for a gas range, as shown.

GEORGE M. COKE.
